DESIGN FOR A PHONOGRAPH TONE ARM

Jean Otis Reinecke, Chicago, Ill., assignor to
Webster Electric Company, Racine, Wis., a
corporation of Wisconsin

Application June 7, 1937, Serial No. 69,728

Term of patent 14 years

To all whom it may concern:

Be it known that I, Jean Otis Reinecke, a citizen of the United States, residing at Chicago, in the county of Cook and State of Illinois, have invented a new, original, and ornamental Design for a Phonograph Tone Arm, of which the following is a specification, reference being had to the accompanying drawing forming part thereof.

Fig. 1 is a side elevation of a phonograph tone arm embodying the design;

Fig. 2 is a top plan view of the tone arm;
Fig. 3 is a front elevational view of the tone arm; and

Fig. 4 is an elevational view of the rear end of the tone arm.

I claim:

The ornamental design for a phonograph tone arm, as shown.

JEAN OTIS REINECKE.
